US00D932093S

(12) **United States Design Patent** (10) **Patent No.:** **US D932,093 S**
(45) **Date of Patent:** **** Sep. 28, 2021**

(54) **ELECTRONIC ATOMIZING DEVICE**

(71) Applicant: **Shenzhen Smoore Technology Limited**, Guandong (CN)

(72) Inventors: **You Shi**, Shenzhen (CN); **Yu Liu**, Shenzhen (CN); **Baosheng Lai**, Shenzhen (CN)

(73) Assignee: **SHENZHEN SMOORE TECHNOLOGY LIMITED**, Shenzhen (CN)

(**) Term: **15 Years**

(21) Appl. No.: **29/710,691**

(22) Filed: **Oct. 25, 2019**

(30) **Foreign Application Priority Data**

May 15, 2019 (CN) 201930235619.4
May 15, 2019 (CN) 201930238582.0

(57) **CLAIM**

The ornamental design for an electronic atomizing device, as shown and described.

DESCRIPTION

FIG. 1 is a perspective view of an electronic atomizing device;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the electronic atomizing device that form no part of the claimed design.

1 Claim, 8 Drawing Sheets
